CHAIR

Mario J. Lo Vico, 135—02 118th St.,
South Ozone Park, N.Y.

Filed Nov. 3, 1958, Ser. No. 53,244

Term of patent 7 years

(Cl. D15—11)

The sole figure is a perspective view of a chair embodying my new design; the essential features are shown in full lines and consist primarily of a one-layer sheet having cut-away corners which expose the supporting frame, and further having supporting straps at the back of the corners.

I claim:

The ornamental design for a chair, as shown and described.
